COMBINED BED AND DRAWER UNIT

Henry G. Zuk, 1431 6th St., Madison, Ill. 62060

Filed Oct. 22, 1965, Ser. No. 87,760

Term of patent 14 years

(Cl. D5—4)

FIG. 2

The side of the bed not shown is a mirror image of the side shown, while the front of the headboard is conventionally flat and unornamented.

I claim:

The ornamental design for a combined bed and drawer unit, as shown and described.
